UNITED STATES PATENT OFFICE

PHILIP A. VOGELMAN, OF NEW YORK, N. Y., ASSIGNOR TO WILLIAM WILLHEIM CO., INC.,
OF NEW YORK, N. Y.

DESIGN FOR A TEXTILE FABRIC OR SIMILAR ARTICLE

Application filed September 24, 1932. Serial No. 45,031. Term of patent 3½ years.

To all whom it may concern:

Be it known that I, PHILIP A. VOGELMAN, a citizen of the United States of America, residing at 15 West 81st Street, in the city of New York, county of New York, and State of New York, have invented a new, original, and ornamental Design for a Textile Fabric or Similar Article, of which the following is a specification, reference being had to the accompanying drawing, forming a part hereof.

The figure is a plan view of a textile fabric showing my new design, the repeat unit of which is contained between the two horizontal dot and dash lines and the two vertical dot and dash lines. The drawing is lined to indicate shading.

I claim:

The ornamental design for a textile fabric or similar article as shown and described.

In testimony whereof I have signed this specification.

PHILIP A. VOGELMAN.
